ART OF DISTILLING EASILY DECOMPOSABLE MATERIALS

Original Filed Dec. 30, 1922

Inventor

WARREN K. LEWIS

By Q. G. Messenger Attorney

Patented Sept. 14, 1926.

UNITED STATES PATENT OFFICE.

WARREN K. LEWIS, OF NEWTON, MASSACHUSETTS, ASSIGNOR TO HUMBLE OIL & REFINING COMPANY, OF HOUSTON, TEXAS, A CORPORATION OF TEXAS.

ART OF DISTILLING EASILY-DECOMPOSABLE MATERIALS.

Application filed December 30, 1922, Serial No. 609,886. Renewed August 7, 1926.

The present invention relates to the art of distillation, particularly vacuum distillation, and will be fully understood from the following description, reference being had also to the accompanying drawing which represents in vertical section a form of apparatus contemplated in the invention.

In the drawing, reference character 1 designates a vaporizing receptacle in the form of a cylindrical shell 1 mounted over a suitable heating chamber 2, and preferably having its neck or upper extension 1' enclosed in a chamber communicating with the heating chamber so as to form a thermal jacket protective against cooling of the vapors before they reach the condenser, as in accordance with my co-pending application, Serial No. 599,963, filed November 10, 1922. Supporting lugs 3 carry the load onto the furnace masonry, or auxiliary framing as desired. From the lower part of the container pipes 4 and 5 may connect to respective tanks, or to the common lines L L' for a battery when operation of a plurality of the stills in a battery is preferred. Where it is desired to use live steam or the like in connection with the distillation a perforated pipe 8 is provided in the bottom.

A cooling or chilling coil 9 with connections 10 is arranged to be supplied with a suitable cooling fluid, the connections in the particular form shown extending through the head 11 which seats against a suitable gasket and is held by bolts. Below the coil 35 is a deflector 12 resting upon projections 13 so as to be conveniently removable, and a conical pan 14 is provided to catch the condensate delivered by the deflector and discharger into a pipe 15, a slip joint 15' being located so that the pan is also removable. Connecting with the pipe is a suitable look box 16; and a valved pipe 16' leads therefrom to a receiver 17, which is provided with a valved pipe 18 below and valved pipes 45 19 at the top, one connecting with a vacuum pump and the other arranged to communicate with the outside air, for relieving the vacuum where desired.

A conduit 20 from the condenser section 50 leads to a vacuum pump and gas holder and preferably through a suitable auxiliary cooler 21 to cool residual gas and which may be used to condense the steam where such has been used, or other vapors as desired, a 55 suitable receiver R with vacuum and vacuum

release connections being provided. A manometer connection 22 is provided, at a convenient location above the foaming level, and thermometers may be located where desirable.

With some liquids under distillation-conditions with low pressures, considerable foaming or priming is apt to occur, and to check any throw over I provide baffles 23 of perforated metal or woven wire screen 65 preferably coarser than ten mesh, these being removably supported on projections 24. The baffles may be flat or may vary in shape as desired but it is desirable to increase the area and clearance for vapor passage, and to this end a cupped or a tapering shape is 70 advantageous.

In operation, liquid to be distilled is admitted from the feed line 4, for instance, drawing from the tank or from the line L 75 according as the still is operating as an isolated unit or as a member of a battery, and in continuous running as the distillation proceeds feed liquid is supplied as desired by regulating the valve. By reason of the 80 uniform cross-sectional area of the still, the vaporizing surfaces of the liquid is maintained substantially constant in area, thus contributing to uniformity of load on the 85 vacuum apparatus, a matter of importance for securing uniformity of product when operating under extreme vacua. The vaporizing surface also is not materially different from the cross-sectional area at the condenser zone in the top of the still, and the 90 condenser being placed in the top of the still a short path for the vapors is secured and a substantial absence of refluxing. If foaming occurs, the rising foam is broken 95 by the foraminous baffle 23. The residuum drawn from the still by the pipe 5 intermittently or continuously either to the tank or by the blocked out line to the next still according as operating singly or in battery. Vapors rising from the distilling 100 liquid encounter the condenser section and are condensed and diverted through the pipe 15 and through the look box 16 to the receiver 17.

The vaporizing receptacle 1 may have its upper end or condenser zone made in a separable piece or integral as desired, the latter in fact affording greater assurance against leaks, and while I have shown the condenser zone as larger in diameter, it will 105 110

be understood that it may be carried up of the same diameter as the vaporizing section if desired.

It will be understood that any desired heating means may be used with the liquid vaporizing receptacle, whether external or internal.

While in describing my invention I have referred to certain specific details, changes may be made, within the spirit and scope of the invention as defined in the following claims.

What I claim is:—

1. Vacuum distillation apparatus, comprising a vertical cylindrical vaporizing receptacle, means for heating the receptacle, condensing means comprising a pipe coil in the path of the vapors, means for supplying a cooling fluid to said coil, a removable collecting pan, a removable deflector arranged beneath the coil and deflecting condensate into the pan, a receiver connected with the pan, removable foraminous baffles adjacent the top of the vaporizing receptacle and adapted to prevent escape of foam therefrom, a conduit leading from the upper portion of the still for the removal of uncondensed vapors therefrom and means for maintaining suction on said conduit.
2. Vacuum distillation apparatus, comprising a vaporizing receptacle, means for heating the receptacle, condensing means in the path of the vapors, means for supplying a cooling fluid to said condensing means, a collecting pan, a deflector arranged beneath the condensing means deflecting con-

densate into the pan, a receiver connected with the pan, a foraminous baffle arranged below the collecting pan, a conduit leading from the upper portion of the still and means for maintaining suction on said conduit.

3. Apparatus of the character described which comprises a vaporizing receptacle, a pipe coil in the upper part of said receptacle connections for supplying a cooling fluid to said coil, a removable collecting pan, a removable condensate deflector arranged below the coil and discharging into the pan, a foraminous baffle below the collecting pan, a conduit for removing vapors from said receptacle, and means for maintaining suction on the conduit.

4. Distillation apparatus which comprises a vaporizing receptacle, a condensing section adapted to receive vapors therefrom, a centrally apertured deflector mounted on the inner surface of said section and having walls inclined inwardly therefrom, a collector pan spaced below said deflector and having an extent not substantially greater than that of the central aperture in the deflector, means for drawing off the condensate from the collector pan, and means for removing uncondensed vapors from the condensing section.

5. Apparatus according to claim 4, in which means are provided for maintaining suction on the drawoff means from the collector pan.

WARREN K. LEWIS.
